UNDERFEED STOKER

Application filed June 22, 1926. Serial No. 117,721.

This invention relates to stokers of the underfeed type, and more particularly to underfeed stokers in which the retort sides are caused to reciprocate, so as to provide a rearward movement and agitation of the fuel bed and a discharge of the incombustible refuse.

In such stokers as heretofore manufactured the reciprocating retort sides have been driven directly by the fuel feeding ram and at the same rate as the ram. As it is undesirable that the retort sides should have as great a movement as the ram, lost motion connections have been introduced to permit an adjustment of the stroke. This results in the retort sides remaining stationary during a large part of the ram stroke, and the benefits to be derived from a more continuous movement are lost. With some fuels, particularly those which tend to form large clinkers and obstruct the flow of air through the fuel bed, it is of great advantage to move the retort sides at a higher rate than the ram, that is, at a greater number of strokes per minute.

Various arrangements have been disclosed in certain of my prior patents, in accordance with which the side bars have been reciprocated at a different rate from that of the ram, but such prior constructions have not embodied the correct principles of stoker operation and so have not proven practical.

It is accordingly the primary object of this invention to overcome the difficulties heretofore met and to provide a stoker construction so arranged that the retort sides may move relative to the coal feeding ram in such a manner that the fuel bed may be kept well broken up by a slicing action occurring between the retorts and adjacent to the tuyères, and in which the side bars are reciprocated relative to the retort bottoms and at a higher rate than that of the rams so as to keep the fuel continually agitated and prevent its moving as a body and so as to prevent the formation of large clinkers in the fire or on the side walls, and in general to improve the operation of a stoker of the "Riley" type.

With this and other objects in view as will

be apparent to one skilled in the art, the invention resides in the combination of parts set forth in the specification and covered by the claims appended hereto.

In accordance with the invention, an underfeed stoker is provided in which the fuel is fed into the retorts from a hopper by means of reciprocating rams. The retort side walls, including tuyères near their upper limits, are arranged to reciprocate also, the bottom of the retorts preferably remaining stationary. Means are provided for reciprocating these retort side walls at a rate different from, and preferably greater than, that of the rams. Means are also provided for adjusting the length of stroke of the retort side walls, and giving them a continuous motion when desired. Means are also provided for stopping the retort side walls independently of the ram in case an exceptional resistance is encountered. If desired, an overfeed grate section may be arranged adjacent to the lower end of the retort, and this may be attached to the retort sides so as to move therewith. Suitable means, such as moving dump plates, may be so located as to cause a discharge of the ash.

Referring to the drawings in which like reference numerals indicate like parts;

Fig. 1 is a longitudinal section of a stoker illustrating one embodiment of the invention, the section being taken on the line 1—1 of Fig. 2;

Fig. 2 is a sectional plan of the stoker, with parts broken away;

Fig. 3 is a detail showing the method of supporting the retort sides at the furnace front;

Fig. 4 is a side elevation, with parts broken away, of the stoker gear box; and

Fig. 5 is a perspective view of the crank shaft which drives the retort sides.

The embodiment of the invention illustrated in the drawings comprises a stoker having three retorts 7, 8 and 9. A hopper 10 is suitably arranged adjacent to the front wall 11 of the furnace so as to provide a receptacle for the fuel. The fuel is pushed into the retorts by means of reciprocating rams 12, driven by connecting rods 14 and crankshaft 15. In a stoker having three retorts, this

crankshaft 15 is preferably provided with throws arranged 120 degrees apart so as to distribute the load on the ram moving mechanism. In the form illustrated, the crankshaft is provided with a worm gear 16 driven by worm 17, which in turn is driven from a suitable source of power.

The stoker retorts may be formed by stationary retort bottoms 19 and movable retort side walls, the latter comprising side bars 20 and air admitting tuyère blocks 21 mounted thereon. These are preferably split on the line between retorts, so that the retort side of adjacent retorts may have relative motion. The side bars 20 may be supported at their outer ends on rods 22 arranged to slide through holes in the ram cases 23. At their inner ends they are preferably attached to shoes 24 arranged to slide on fixed base plates 26, which are bolted to I-beams 27. The ends of these I-beams rest on the foundations of the furnace side walls. Adjacent to the lower ends of the retorts, and mounted on the side bars so as to reciprocate therewith, are overfeed grate sections 28, which extend across the entire width of each retort, from one side bar to another. Hinged to the sliding shoes 24 and arranged to move therewith and to partially close the opening adjacent to the bridge wall 29 are dump plates 30. The movement of these plates produces a constant discharge of ash from the furnace, and their position can be adjusted or a complete dump made by turning dump shaft 31, and so moving rack 32 longitudinally by its engagement with pinion 33. At the front of the stoker a front plate 35 is provided so as to form an air chamber for the introduction of forced draft from a suitable fan. The stoker may be supported at the front on pipe columns 36.

The construction as heretofore described is well known in the art, and similar stokers are disclosed in the patents to Riley Nos. 1,090,651 and 1,322,822. In order to produce a more thorough agitation of the fuel bed than has been possible heretofore, means have been provided for reciprocating the retort side walls continuously when desired and at a higher rate than the rams. It is highly desirable at certain times to give these retort sides a comparatively rapid continuous motion. This is particularly true when the fire is in a banked condition and there is a sudden heavy load demand, requiring the boiler being fired to be thrown on the line in the shortest possible time. By moving the retort sides rapidly and continuously, and especially by providing for relative motion between the sides of adjacent retorts, the fuel bed, which tends to coke over more or less solidly when banked, will be quickly broken up so as to allow air to pass therethrough. In this way the boiler can be brought to a high rating very quickly.

The drawings illustrate one means by

which this can be accomplished. The two side bars of each retort are joined by a rod 40. Attached by a suitable bearing to each rod 40 is a connecting rod 41. The several connecting rods are driven by a crankshaft 42. The amount of throw on this crankshaft determines the maximum stroke of the side bars, and this is preferably much less than the stroke of the rams. In a three retort stoker, this crankshaft is preferably made with the three throws 120 degrees apart, as illustrated particularly in Fig. 5. In this way, it is evident that there will always be relative motion between the sides of adjacent retorts, and lines of cleavage will be formed in the fuel bed over the tops of the tuyères. This provides an opening for the passage of air and an exit for the hot gases, which otherwise tend to strike back and injure the fuel supporting surfaces. This relative motion between retorts is also of the greatest importance in keeping the fuel bed agitated, and preventing the formation of large clinkers.

The rod 41 passes through a slot 43 in the front plate 35, and in order to prevent the escape of air into the boiler room through this slot, a closing plate 44 is provided. This plate has an opening only slightly larger than the rod 41, through which the latter passes. In operation the rod 41 moves up and down in the slot 43, and plate 44 moves with it, being prevented from moving away from the front plate by guides 45.

It is highly desirable that means should be provided for varying the stroke of the retort side walls, and for giving them a continuous motion when the stroke is adjusted to the maximum amount. In this way, low portions of the fuel bed can be quickly filled in. Moreover, by producing rapid agitation of the burning fuel, it is possible to meet sudden demands for steam from the boiler being fired.

In order to accomplish this, crankshaft 42 is arranged to drive each connecting rod 41 by means of a block 46 arranged to slide on the rod between collars 47 and 48, which are fixed on the rod by pins 49 and 50 respectively. These pins pass through holes in the rod and collars. As shown in Fig. 4, several holes may be provided in the rod, so that the position of collar 47 may be varied, and the length of the side bar stroke adjusted. If desired, collar 47 may be located closely adjacent to block 46, so that the retort sides will be given a continuous reciprocating motion. Pins 47 and 48 are preferably of sufficient strength to drive the side bars under ordinary conditions, but so proportioned that they will shear if any exceptional resistance is encountered during either a forward or backward stroke, so as to prevent any further damage to the stoker driving mechanism. Such a construction is of the greatest advantage, as is well

known to those skilled in the art. At times, hard clinkers become wedged against the bridge wall so as to impede the motion of the side bars. There is also a danger of tramp iron from the coal becoming lodged between the relatively moving tuyères. Without some safety device, such an occurrence might cause destruction of expensive parts of the machine. It is evident that the shearing pins 10 shown in Fig. 4 can be replaced very easily and cheaply after the obstruction is removed.

On crankshaft 42 is mounted a worm gear 52, which is driven by a worm 53. Worm 53 is keyed to shaft 54, which is mounted in suitable bearings 55. Shaft 54 preferably extends through worm 17 also, and this construction affords an advantage in that the two worms can be made of opposite hand and their thrusts will hence to a certain extent counteract each other. It is also possible in this way to simplify the construction and drive the rams and retort sides from the same source of power and in timed relation. Each worm is shown in Fig. 4 as being constructed 25 with a single thread, gear 52 as having 16 teeth, and gear 16 as having 24 teeth. It is obvious then that under these conditions, the retort sides will move at a different rate from the rams. In the case illustrated, the sides 30 of any particular retort will make three strokes while the ram is making two. This ratio can of course be made anything desired.

A suitable driving means is connected to the stoker shaft 60, and this in turn drives worm shaft 54 through suitable gearing, not shown. If desired, this gearing may be of the two speed type, as disclosed in the patent to Taylor No. 1,486,311. In this case, the 40 lever 61 serves as a means for stopping the stoker, or for changing from one speed to another.

The operation of the stoker will be apparent from the above disclosure. Fuel, usually coal, is fed from the hopper 10 into the retorts by the reciprocating rams 12. In the retorts the volatile constituents of the fuel are driven off by the heat of the fire above, and these gases pass upward through the layer of burning fuel, where they are consumed. After the gases are driven off, the remaining coke is gradually forced upward and rearward, past the streams of air issuing from the openings in the tuyères 21. The reciprocating retort sides keep the fuel 50 bed well broken up and continually feed it rearward towards the bridge wall 29. The combustible is almost completely burned out on the overfeed grate sections 28, which move with the retort sides, and feed the ash and clinkers on to the dump plates 30. Here the 60 incombustible matter is continuously agitated, crushed, and ejected from the furnace. The stoker is driven from any suitable source of power, which is connected to shaft 60. 65 This in turn drives the worm shaft 54

through suitable gearing, causing the two crankshafts to revolve in timed relation. In the embodiment illustrated, the retort sides of any particular retort make three strokes while the corresponding ram is making two 70 strokes. In other words, the side walls go in, out, and in, while the ram is going in and out. Relative motion between adjacent retort sides is provided for in the design of the crankshaft. The relative position of the various parts at one point in the cycle is illustrated in Fig. 2, and their respective directions of motion are shown by arrows. In retort 7, the ram has moved a short distance on its rearward stroke towards the furnace, and the retort sides have moved a short distance on their forward stroke. In retort 8, the ram has just started its forward stroke, and the retort sides have just started their rearward stroke. In retort 9, the ram 80 has nearly completed its forward stroke, and the retort sides have nearly completed their rearward stroke. In Fig. 1, and Fig. 2, the retort sides are illustrated as moving continuously, without lost motion. Their stroke 85 can be changed easily, as shown in Fig. 4, by moving pin 49 and collar 47 to another hole. It will be observed that this construction causes the reciprocable parts to move in a timed relation and with a frequently recurring cyclic movement, which in the illustration given has a 3 to 2 ratio, the ram 90 making two full double strokes while the side bars move three double strokes to complete the cycle. A non-cyclic movement, or 100 one recurring only at infrequent intervals, may develop undesirable characteristics in the condition of the fuel bed.

It will be evident to those skilled in the art, that the invention provides an underfeed stoker by means of which the furnace conditions can be more easily controlled than by stokers as heretofore disclosed. Simply by adjusting the side bar motion from a short intermittent stroke to a comparatively long 105 continuous stroke, the fuel bed can be built up, leveled, or thinned out as desired, clinkers can be easily broken up and fed to the dump plates, and a banked fire quickly brought into a condition to carry a heavy 110 load.

Having thus described the invention of R. SANFORD RILEY, deceased, what is claimed as new and desired to secure by Letters Patent is:

1. A stoker comprising a retort having side walls reciprocable to agitate and move the fuel bed, a ram reciprocable to move fuel into the retort, and means to move the ram and the side walls at different rates and in a manner to provide considerable relative frequently recurring cyclic movement between the two. 125

2. An underfeed stoker comprising retorts having stationary bottoms and movable side 130

walls, reciprocable rams for feeding fuel into said retorts, means for actuating said rams, and means for reciprocating the side walls of a given retort in the same direction at the same time and at a rate different from that of the corresponding ram in a frequently recurring cycle relative thereto.

3. An underfeed stoker comprising retorts having movable side walls, reciprocable rams for feeding fuel into said retorts, a crank-shaft and connecting rods for driving said rams, a worm gear on said crankshaft, a second crankshaft and connecting rods for driving said retort side walls, a worm gear on said second crankshaft, and a rotatable shaft having worms thereon in mesh with said worm gears, said worms and worm gears being so constructed that the crankshafts may be driven in timed relation at different rates.

20 4. An underfeed stoker comprising parallel retorts having bottoms and movable side walls carrying tuyères thereon, a reciprocable ram to feed the fuel into each retort, a driving mechanism, connections between said mechanism and rams to reciprocate the latter, and an adjustable lost motion connection between said mechanism and the side walls which moves them through a variable distance at a higher rate than the rams move and in a frequently recurring cycle relative thereto.

25 5. An underfeed stoker comprising retorts having movable side walls, reciprocable rams for feeding fuel to said retorts, a crank shaft and connecting rods for driving said rams, a worm gear on said crank shaft, a second crank shaft and connecting rods for driving said retort side walls, a worm gear on said second crank shaft, and a rotatable shaft having worms thereon in mesh with said worm gears, said worms being of opposite hand whereby the thrusts caused by said worm gears will tend to counteract each other.

40 6. An underfeed stoker comprising retorts having stationary bottoms and movable side walls, means for moving the side walls of each retort simultaneously in the same direction, tuyères mounted on the side walls to move therewith, reciprocable rams for feeding fuel into said retorts, means for reciprocating the rams at one rate and the side walls at a different rate in a frequently recurring cyclic relationship, and overfeed grate sections forming continuations of said bottoms which grates are connected to said side walls and arranged to reciprocate therewith.

45 7. An underfeed stoker comprising retorts having movable side walls, reciprocable rams for feeding fuel into said retorts, a crank-shaft and connecting rods for driving said rams, a separate crank shaft and connecting rods for driving said retort side walls, means for adjusting the length of stroke of said retort sides, and means for driving said crank-

50 shafts at different rates in a timed frequently recurring cyclic relation.

8. An underfeed stoker comprising a retort having a stationary bottom and movable side walls, means for moving the side walls simultaneously in the same direction, tuyères mounted on the side walls to move therewith, a reciprocable ram for feeding fuel into said retort, means for reciprocating the ram and the side walls at different rates in a timed relation and a frequently recurring cyclic movement, and means for varying the length of stroke of the retort sides independently of the length of ram stroke.

Signed at Worcester, Massachusetts, this 15th day of June, 1926.

KATHARINE H. RILEY,
*Executrix of the will of R. Sanford Riley,
Deceased.*
